U.S. PATENT 3,522,802
TRACTION APPARATUS

This invention relates to the application of traction to a patient.

It has heretofore been suggested that for various diseases and conditions of patients, traction might be applied to the spine. Prior art devices usually comprise a body encircling belt to which straps are connected which extend along the sides of the body of the patient. Weights are connected to the straps for applying the pulling or traction force.

In such devices, there is a tendency for the belt to slip and for the traction force to be taken substantially by the waist producing substantial discomfort.

Among the objects of the invention are to provide a method and apparatus for more efficiently applying traction force to a patient; to provide a novel traction belt that can effectively be used for both supporting the abdomen and applying the traction force; to provide a novel traction belt that is comfortable on the wearer; and to provide a traction apparatus that is relatively simple and low in cost.

Basically, the method disclosed herein comprises applying the traction force to the outermost and uppermost portions of the pelvis in a direction generally toward the feet of the patient and toward the longitudinal center line of the patient. The apparatus disclosed herein comprises a belt having a back portion and bifurcated body encircling front portions, the upper said bifurcated front portion adapted to extend across the waist of the patient and the lower bifurcated front portion adapted to extend across the abdomen of the patient. Pressure pads are slidably supported on the upper bifurcated belt portion adjacent the uppermost and outermost portions of the pelvis. A strap is slidably connected to each pressure pad and extends across the front and rear of the patient and is connected to a spacer bar which is positioned generally centrally of the patient. The traction weights are connected to the spacer bar by a flexible member such as a rope.

In the drawings:

FIG. 1 is a plan view of a patient positioned in the apparatus embodying the invention.

FIG. 2 is a side elevational view of the apparatus shown in **FIG. 1**.

FIG. 3 is a fragmentary plan view of the traction belt portion of the apparatus.

FIG. 4 is a fragmentary plan view of a modified form of traction belt.

FIG. 5 is a fragmentary sectional view on an enlarged scale taken along the line 5-5 in **FIG. 3**.

FIG. 6 is a fragmentary sectional view on an enlarged scale taken along the line 6-6 in **FIG. 3**.

Referring to **FIGS. 1** and **2** the invention is adapted to be used for applying traction to a patient **P** when he is reclining on a bed **10** or similar support. Basically, a traction belt **11** is worn by the patient and the traction forces are supplied by a weight **12** which is connected to a rope **13** trained over a pulley **15** that is mounted on the bed. In accordance with the invention, the traction forces are applied to the upper and outermost portions of the pelvis in a direction extending across the front and rear of the patient toward the feet and toward a center line through the patient, represented by the arrows in **FIG. 1**. By this arrangement, the traction forces are more perpendicular to the upper and outer portions of the pelvis and there is less tendency for slipping.

More specifically, as shown in **FIG. 3** the belt comprises a rear portion **15** that extends across the small of the back and has pockets **16** in which stiffeners of whale bone, steel or the like are positioned. Bifurcated upper and lower belt portions **18, 19** extend from the rear portion **15** across the side and the front of the wearer. Straps **20** are connected to one of the bifurcated portions **18** and are adapted to be fastened by appropriate fasteners **21** to the other of the upper belt portions **18**. Similar straps **22** and buckles **23** are adapted to interconnect the lower belt portion **19**. When on the wearer, the upper belt portions **18** extend across the waist while the lower belt portions **19** extend across the upper portions of the hips.

FIG. 2

Slidable loops **24** are connected to narrow portions **25** at the upper belt portions **18** and slidably support elongated pressure pads **26**, each of which comprises a pocket **27** supporting a pad **28** of foam rubber or the like. When on the wearer, the pads **26** are thus supported in overlying relationship to the upper and outermost portions of the pelvis. A strap **29** is threaded through loops **30** on each pad **26**. One portion **29a** of each strap **29** is adapted to extend across the front of the wearer, generally along the line of the joint between the leg and the torso while the other portion **29b** of the belt **29** extends across the rear of the patient along the line connection between the leg and the torso. Each of the belts **29** is adjustable in length as at **30** and is connected to D loops at the ends thereof whereby it is connected to a spacer bar **32** positioned between the legs of the patient. The end of the rope **13** is fastened to an eye bolt **33** on the spacer bar **32**.

On each individual patient, the shape and exact position of the pelvis varies. Accordingly, the length of the strap **29** is adjusted so that the force applied to each upper and outermost portion of the pelvis extends as nearly normal thereto as possible so that there is a minimum tendency for slippage to occur.

The traction belt **11** can be worn by the patient when traction is not being applied merely by disconnecting the belts **29**. When so worn, the belt provides substantial support for the abdomen and is comfortable since there is no undue strain on either the waist or abdomen.

By utilizing a belt which has bifurcated body encircling portions, it is possible to snugly engage both the waist and pelvis of the patient. Since the circumferential dimensions of the waist and pelvis are normally different from one another, the two portions of the belt may be tightened and thereby expose a greater portion of the upper and outermost parts of the pelvis to which the force is to be applied. In use, the upper portion of the belt is tightened to expose as much of the hip bone as possible on which the traction pad rest is tightened to provide the greatest comfort for the patient.

In the form of the invention shown in **FIG. 4**, traction belt **35** is made so that it extends across the waist only and does not have an abdomen encircling portion. Specifically, the belt includes a rear portion **36**, a narrow side portion **37** and a front portion **38** which are interconnected by straps **39** and buckles **40**. Narrow portions **37** support the loops **24** and pads **26** as in the previous form of the invention. In use, the belt **35** is applied around the waist of the patient and the straps **29** are adjusted in the same manner as in the previous form of the invention.

In addition to use of the belt for applying traction, the increased comfort achieved by the novel belt embodying the invention permits its use as a surgical belt. By extending portions of the belt upwardly along the belt, increased support can be achieved as may be desired.

I claim:

1. In an apparatus for applying traction to a reclining patient, the combination comprising
a belt having a back portion and bifurcated body encircling front portions,
one said bifurcated front portion of the belt adapted to extend across the waist of the torso of the patient,
the other said bifurcated front portion of the belt adapted to extend across the abdomen of the patient,
pressure pads,
means for supporting pads on the side of said upper portions of said belt,
the upper portion of the belt adapted to support said pressure pads generally in overlying relation to the uppermost and outermost portions of the pelvis,
force applying straps connected to said pad,
one of said straps adapted to extend from its respective pad across the front of the wearer,
the other of said straps adapted to extend from its respective pad across the rear of the wearer,
a spacer bar,
the ends of said straps being connected to said spacer bar for positioning along the longitudinal center line of the patient,

and means for applying a force to said spacer bar in a direction extending longitudinally of the patient.

2. The combination set forth in Claim 1 wherein said means for applying a force comprises
  - weight and pulley means connected to said spacer bar and adapted to be supported by the bed or similar device on which the patient is reclining.
3. The combination set forth in Claim 1 wherein each said pad is slidably connected to its respective front portion.
4. The combination set forth in Claim 1 wherein the side of each one said front portion is of substantially lesser width than the front of each said front portion.
5. The combination set forth in Claim 1 wherein each one said front portion is of lesser width than each other said front portion.
6. The combination set forth in Claim 1 wherein the back portion of said belt is vertically reinforced.
7. In an apparatus for applying traction to a reclining patient, the combination comprising
  - a belt having a back portion and body encircling front portion adapted to extend across the waist of the torso of the patient,
  - a pair of pressure pads,
  - each said pad being slidably connected to the side of said portion of the belt for supporting the pressure pad

15

20

25

generally in overlying relation to the uppermost and outermost portion of the pelvis,
 force applying straps slidably connected to said pad,
 one portion of each of said straps adapted to extend from its respective pad across the front of the wearer,
 the other portion of each of said straps adapted to extend from its respective pad across the rear of the wearer,
 a spacer bar,
 the ends of said straps being connected to said spacer bar for positioning along the longitudinal center line of the patient,
 and means for applying force to said spacer bar adapted to extend longitudinally of the patient.

8. The combination set forth in Claim 7 wherein said means for applying a force comprises
  - weight and pulley means connected to said spacer bar and adapted to be supported by the bed or similar device on which the patient is reclining.
9. The combination set forth in Claim 7 wherein each said pad is slidably connected to its respective front portion.
10. The combination set forth in Claim 7 wherein the side of each one said front portion is of substantially lesser width than the front of each said front portion.
